UNITED STATES PATENT OFFICE.

JOSEPH B. FISCHER, OF CHICAGO, ILLINOIS, ASSIGNOR OF ONE-FOURTH TO ADAM P. D. MEYER, OF CHICAGO, ILLINOIS.

BALLOT-BOX.

1,207,008.

Specification of Letters Patent.

Patented Dec. 5, 1916.

Application filed February 26, 1916. Serial No. 80,598.

To all whom it may concern:

Be it known that I, JOSEPH B. FISCHER, a citizen of the United States of America, and a resident of Chicago, in the county of Cook, 5 State of Illinois, have invented certain new and useful Improvements in Ballot-Boxes, of which the following is a specification.

This invention relates to ballot boxes in which the ballots as cast are recorded numerically, and has for its various objects:— 10 To provide a simple and efficient formation and association of parts whereby the ballots are serially fed into the receiving compartment, and a stoppage of the feeding mechanism automatically effected after each 15 ballot is fed into the box, thus requiring a manual release before a succeeding ballot can be entered.

In the accompanying drawings:—Figure 20 1, is a plan view of a portion of a ballot box, with parts broken away and in section, illustrating the general arrangement of parts in the preferred form of the present invention. Fig. 2, is a detail vertical section on line 25 X—X, Fig. 1, of the operating and registering mechanisms. Fig. 3, is a sectional elevation of said mechanisms on a plane at right-angles to the vertical plane on which Fig. 2, is made. Fig. 4, is an enlarged detail vertical section on line X'—X', Fig. 1. 30 Fig. 5, is a detail elevation of the inner face of the operating hand crank of mechanism. Similar reference numerals indicate like 35 parts in the several views.

Referring to the drawings, 1 designates an 40 end portion of a box or receptacle adapted to receive the series of ballots and having the usual locked cover 2, by means of which election officials may have access to the ballots contained within the box.

3 designates an entry slit provided in the cover 2 for the successive entry of the ballots. Said entry slit is preferably formed in a plate 4 by which the frame or housing 45 of the mechanism is supported in a depending manner, and said plate 4 is in turn set in an opening in the cover 2, and preferably flush with the top surface of said cover, as shown.

5 and 6 designate companion rollers or drums journaled immediately beneath the entry slit 3 aforesaid, and disposed at opposite sides thereof as shown, so as to receive and by their manual rotation, draw the bal-

lots into the receiving compartment of the 55 ballot box. With a view to an efficient operation, the rollers 5 and 6, are preferably formed with perimeters of an elastic material, such as india rubber, and longitudinally fluted, as shown more particularly in 60 Figs. 1 and 3. And in the preferred structure illustrated in Fig. 1, the journal pins of one roller 5, will have fixed bearings in the supporting frame, while the journal pins of the companion roller 6, will have bearings 65 in a horizontally movable yoke 7, yieldingly forced in one direction by a spring 8, to 70 yieldingly hold the rollers 5 and 6 in close peripheral contact and cause the same to rotate in union.

9 designates a marking block of any usual 75 nature in one of the rollers 5 or 6 aforesaid, and adapted to impress upon a passing ballot an identifying mark of an election judge or other official.

10 designates a pinion fixed on one of the journal pins of the roller 5 aforesaid, and adapted to receive rotation from a gear 80 wheel 11 which receives rotation from the operating mechanism now to be described.

12 and 13 designate longitudinally alined 85 trunnions, the inner one 12 of which is journaled in a bearing sleeve or hub 14 of the supporting frame aforesaid, and carries on its inner end the gear wheel 11 aforesaid. The outer end of the trunnion 12 is formed 90 into one member of a toothed clutch 15, with the companion member of said clutch formed in the adjacent end of the outer and removable trunnion 13 aforesaid.

In the preferred construction shown in Fig. 4, the inner trunnion 12 is formed with an axial orifice adapted to receive a correspondingly formed stem 16 on the outer trunnion 13, with a view to holding the 95 parts in proper operative alinement in practical use. The outer trunnion 13 is formed with a central guide orifice for the reception of the guide stem of the latch actuating member hereinafter described, and said 100 guide orifice is in turn formed with an enlarged portion for the reception of a spring by which said latch actuating member is moved in one direction.

17 designates a hand crank fixedly attached to the outer end of the outer trunnion aforesaid, for the convenient rotation of the same.

18 designates a movable stop pin guided in the supporting frame aforesaid, and movable into and out of the path of the hand crank 17 aforesaid, and constituting 5 the movable member of the latch mechanism adapted to prevent a manual rotation of the hand crank, when said stop pin is in its normal position.

19 designates a spring tending to move 10 and hold the stop pin 18 in the path of the hand crank 17 aforesaid.

20 designates a curved stop recess formed 15 in the inner face of the hand crank 17, and adapted to move over and engage the projecting end of the stop pin 18, to cover said pin and prevent tampering therewith.

21 designates the latch actuating head or member above referred to, and which is provided with a guide stem 22 moving in the 20 axial guide orifice of the outer trunnion 13, and having an associated spring 23, by which said head 21 is moved and held in its outward position as illustrated in Figs. 3 and 4.

25 24 designates an operating stem fixedly attached to the head 21 and moving in a guide slot formed in the hand crank 17, in alinement with the abutting portion of the stop recess 20 and with the stop pin 18, as 30 shown.

The arrangement is such that as the actuating head 21 is pushed inwardly by the thumb of the operator manipulating the hand crank 17, the stop pin 18 is pushed 35 out of the stop recess 20, leaving the hand crank 17 free to receive a single revolution. More than a single revolution of said hand crank is prevented by the reentry of the stop pin 18 into the recess 20, as the hand 40 crank nears the end of such single revolution, and so that a fresh manipulation of the actuating head 21 is required at each subsequent revolution of said hand crank, each revolution being adapted to effect the 45 deposit of a single ballot.

With the present improvement, the hand crank 17 with the described accessories carried thereby, are removable, as a whole from the ballot box structure, and are intended to remain in the possession of the 50 election judge or other official having the deposit of ballots in charge, and thus preventing the deposit of any spurious ballots.

25 55 25 designates a counting or registering mechanism of any ordinary and suitable construction, with its primary shaft 26 provided with an operating arm 27, on its outer end.

28 designates a tappet or lug carried at 60 the side of the gear wheel 11 aforesaid, and adapted in each revolution of said wheel to impart movement to the arm 27 aforesaid, and effect a unit registry movement of the registering mechanism afore- 65 said.

Having thus fully described my said invention, what I claim as new and desire to secure by Letters Patent is:—

1. A ballot box formed with an inlet slit for the ballots, a pair of feeding rollers associated with said inlet slit, a pinion associated with one of said rollers, a gear wheel operatively engaging said pinion and provided with a clutch member, a removable hand crank provided with a clutch member, adapted for engagement with the aforesaid clutch member of the gear wheel, means for stopping said hand crank after a complete revolution, the same comprising a stop pin movable laterally to and from said hand crank and a lateral stop on said hand crank adapted for engagement with said stop pin, and manually actuated means for moving said stop pin out of the path of said lateral stop, substantially as set forth.

2. A ballot box formed with an inlet slit for the ballots, a pair of feeding rollers associated with said inlet slit, a pinion associated with one of said rollers, a gear wheel operatively engaging said pinion and having a bearing trunnion the outer end of which has a clutch formation, a removable hand crank having a lateral trunnion one end of which has a clutch formation 95 adapted for engagement with the clutch formation of the trunnion of the gear wheel aforesaid, and means for stopping said hand crank after a complete revolution, the same comprising a lateral stop member on the 100 hand crank, a stop member on the supporting frame and manually actuated means carried by the hand crank for effecting a separation of said stop members, substantially as set forth.

3. A ballot box formed with an inlet slit for ballots, a pair of feeding rollers associated with said inlet slit, a pinion associated with one of said rollers, a gear wheel operatively engaging said pinion and having a bearing trunnion the outer end of which has a clutch formation, a removable hand crank having a lateral trunnion, one end of which has a clutch formation 110 adapted for engagement with the clutch formation of the trunnion of the gear wheel aforesaid, means for stopping said hand crank after a complete revolution, and manually actuated means for releasing said stopping means slidingly mounted on said hand crank, substantially as set forth.

4. A ballot box formed with an inlet slit for the ballots, a pair of feeding rollers associated with said inlet slit, a pinion associated with one of said rollers, a gear wheel operatively engaging said pinion and provided with a clutch member, a removable hand crank provided with a clutch member adapted for engagement with the aforesaid clutch member of the gear wheel, 125

means for stopping said hand crank after a complete revolution, the same comprising a stop pin movable to and from said hand crank and a curved stop recess in said hand crank, and manually actuated means for moving said stop pin to a release position, substantially as set forth.

5. A ballot box formed with an inlet slit for ballots, a pair of feeding rollers associated with said inlet slit, a pinion associated with one of said rollers, a gear wheel operatively engaging said pinion and provided with a clutch member, a removable hand crank provided with a clutch member

adapted for engagement with the aforesaid 15 clutch member of the gear wheel, means for stopping said hand crank after a complete revolution, the same comprising a stop pin movable to and from said hand crank and a curved stop recess in said hand crank, and 20 a head movable on said hand crank and having an operating stem in alignment with the stop pin aforesaid and adapted to move the same into a release position, substantially as set forth.

25 Signed at Chicago, Illinois, this 21st day of February, 1916.

JOSEPH B. FISCHER.
